UNITED STATES PATENT OFFICE.

PETER J. NAGLE, OF ROCHESTER, NEW YORK, ASSIGNOR TO CEDAROID CO. INC., OF ROCHESTER, NEW YORK, A CORPORATION OF NEW YORK.

CARDBOARD RECEPTACLE AND METHOD OF FORMING THE SAME.

1,288,132.

Specification of Letters Patent.

Patented Dec. 17, 1918.

Application filed May 1, 1918. Serial No. 231,928.

To all whom it may concern:

Be it known that I, PETER J. NAGLE, a citizen of the United States, and resident of Rochester, in the county of Monroe and State of New York, have invented certain new and useful Improvements in Cardboard Receptacles and Methods of Forming the Same, of which the following is a specification.

10 The present invention relates to cardboard receptacles and to the method of forming the same. An object of this invention is to provide for making a receptacle from thick cardboard stock in which the corner between two walls formed from a single piece of stock will be strong and durable. Another object of the invention is to provide a crease or score in cardboard stock which will permit the utilization of two rotary knives without any clogging action.

15 To these and other ends, the invention consists of certain parts and combinations of parts, all of which will be hereinafter described, the novel features being pointed out in the appended claims.

In the drawings:—

20 Figure 1 is a plan view of a portion of a bottom, a front, and a rear wall of a receptacle scored or creased in accordance with this invention;

Fig. 2 shows a vertical section through a portion of a sheet of cardboard with two rotary cutters coöperating therewith;

25 Fig. 3 is an enlarged sectional view showing the cardboard after it has been scored or creased in accordance with this invention; and

Fig. 4 is an enlarged sectional view showing two walls of the receptacle bent at right angles to close the two grooves, compress the stock between the grooves, and break the stock on its opposite side between the grooves.

At the present time it is customary, when 5 receptacles are formed from thick cardboard, to provide in one face of the cardboard a V-shaped groove or score, preferably by two fixed knives arranged at angles to each other and past which the material is caused to travel. It has also been suggested to form these grooves by means of two rotary knives whose axes are at slight angles to each other. When the stationary knives are

used such knives must be sharpened very frequently, and when the rotary knives are used there is a great tendency for clogging 55 action due to the arrangement of the rotary knives. In both instances, when the stock is bent to bring the two portions on opposite sides of the groove at right angles to each other and to close said groove, the stock breaks directly opposite the apex of the groove, so that only a small amount of stock forms a connection between the two walls. It is the purpose of this invention to score 60 or crease the board so that the stock, when breaking on the opposite side of the crease or score, will still have sufficient body between the two walls to provide a firm connection. It has been found also that, when 65 the stock is scored or creased in accordance with this invention, it is possible to use two rotary knives without the production of any clogging action.

Referring more particularly to the drawings, 1 indicates the bottom wall of the receptacle and 2 the side walls, all of which are formed from a single piece of stock, the walls in the drawings lying in the same plane. On opposite sides of the bottom wall 75 1 the stock is formed with two grooves 3 which preferably have converging walls and lie in close proximity to each other with a rib or portion 4 between them, this rib being below the plane of the grooved face of the 80 stock so that the stock between the grooves 85 is thinner than the portions on the outer sides of the grooves.

The grooves may be formed by two beveled cutters 5 journaled on arms 6 which 90 depend from blocks secured to the usual scoring machine. The opposed faces of the two cutters 5 are at right angles to the common axes of the cutters, while the opposite face 8 of each cutter is at a slight 95 angle to said axis. The stock is caused to travel past the cutters, and in doing so the grooves 3 are cut in the stock and at the same time a thin piece of the stock between the two grooves is peeled off, due to the 100 laminated structure of the cardboard, thus reducing the thickness of the material between the grooves 3 in the manner shown in Fig. 3.

After the groove is formed the side wall 105 2 is bent at right angles to the bottom wall

1, as shown in Fig. 4, thus closing the grooves 3 and at the same time compressing the rib formed between the grooves in the manner shown at 4^a in Fig. 4, while breaking or splitting the stock, as shown at 9 in Fig. 4, this break or split occurring between the grooves 3, so that the break or split is out of line with the apexes of the bottoms of the grooves 3, and in this way 10 a greater amount of stock is secured in the corner between the walls 1 and 2.

To the end that the material shall break on a straight line, the under side of the cardboard may be provided with a surface score 15 as at 10, Fig. 3, which may be formed in the scoring machine by a rotary cutter operating on the under side of the board.

From the foregoing it will be seen that, according to this invention, it is possible to 20 obtain a receptacle made from thick cardboard and having two angularly arranged walls formed from a single piece of stock and connected by a corner formed on one face of the stock by two adjacent closed 25 grooves with the stock between the grooves compressed, and the opposite side of the stock broken between the grooves. This result is obtained by scoring or cutting two 30 grooves having converging walls and situated in close proximity to each other, bending the stock to close the grooves, and to compress the stock between the grooves, while at the same time breaking the opposite face or side of the stock between the 35 grooves.

What I claim as my invention and desire to secure by Letters Patent is:—

1. A sheet of cardboard for forming receptacles having two grooves with converging walls situated in close proximity on one side of the stock, the material between the grooves being thinner than that on opposite sides of the grooves, said sheet also

having a groove on the opposite side of the stock between the first two named grooves. 45

2. The method of forming receptacles from cardboard which consists in providing two adjacent grooves in the stock and bending the stock in a direction to close the grooves and to break the stock on the opposite side between the grooves. 50

3. The method of forming receptacles from cardboard which consists in providing two adjacent grooves with converging side walls, removing part of the stock between the grooves and bending the stock in a direction to close the groove and to break the stock on the opposite side between the grooves. 55

4. The method of forming receptacles 60 from cardboard which consists in simultaneously providing two adjacent grooves in the stock and removing part of the material between the grooves; and then bending the stock in a direction to close the grooves, to 65 compress the stock between the grooves and to break the stock on the opposite side between the grooves.

5. The method of forming receptacles 70 from cardboard which consists in providing in one face of the stock two adjacent grooves and in the opposite face a single groove between the two grooves, and bending the stock to close the two grooves and to break the stock at the single groove. 75

6. The method of forming receptacles from cardboard which consists in providing in one face of the stock two adjacent grooves, thinning the stock between the grooves, providing in the opposite face of the stock 80 a groove between the two grooves, and bending the stock to close the two grooves, to compress the stock between the grooves and break the stock at the single groove.

PETER J. NAGLE.
